DESIGN FOR A DOLL'S CRADLE

Frank A. Lisi, Philadelphia, Pa.

Application January 17, 1946, Serial No. 125,668

Term of patent 3½ years

(Cl. D34—15)

To all whom it may concern:

Be it known that I, Frank A. Lisi, a citizen of the United States, residing in the city of Philadelphia, county of Philadelphia, and State of Pennsylvania, have invented a new, original, and ornamental Design for Doll's Cradle, of which the following is a specification, reference being had to the accompanying drawing, forming part thereof.

Figure 1 is a perspective view of a doll's cradle showing the design; and

Figure 2 is a plan view of the doll's cradle shown in Fig. 1 on a reduced scale.

I claim:

The ornamental design for a doll's cradle, substantially as shown and described.

FRANK A. LISI.
